Primary Examiner—Mimosa De(74) *Attorney, Agent, or Firm*—Baker & Daniels LLP(57) **CLAIM**

The ornamental design for a bench, as shown and described.

DESCRIPTION

FIG. 1 is a perspective view of a bench according to a first embodiment of our new design;

FIG. 2 is a front/rear view thereof;

FIG. 3 is a left/right side view thereof; and

FIG. 4 is a top view thereof.

FIG. 5 is a perspective view of a bench according to a second embodiment of our new design;

FIG. 6 is a front/rear view thereof, it being understood that the left/right side view is the same as FIG. 3; and

FIG. 7 is a top view thereof.

FIG. 8 is a perspective view of a bench according to a third embodiment of our new design;

FIG. 9 is a front/rear view thereof, it being understood that the left/right side view is the same as FIG. 3; and,

FIG. 10 is a top view thereof.
